UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A POWDER-RECEPTACLE BODY.

49,119.

Specification for Design.

Patented May 30, 1916.

Application filed February 19, 1915. Serial No. 9,444. Term of patent 7 years.

To all whom it may concern:

Be it known that I, EDMUND HOFFMAN, a citizen of the United States, residing at Brooklyn, in the county of Kings and State of New York, have invented a new, original, and ornamental Design for a Powder-Receptacle Body, of which the following is a specification, reference being had to the accompanying drawing, forming a part thereof.

On the drawing the figure is a perspective view of the powder receptacle body, embodying the design.

I claim:

The ornamental design for a powder receptacle body, as shown.

EDMUND HOFFMAN.
